UNITED STATES PATENT OFFICE.

CHARLES T. E. GOULD, OF CHICAGO, ILLINOIS, ASSIGNEE OF ONE-THIRD TO EDWARD HILKER, OF CHICAGO, ILLINOIS.

SEWING-MACHINE.

1,080,549.

Specification of Letters Patent.

Patented Dec. 9, 1913.

Application filed September 13, 1912. Serial No. 720,206.

To all whom it may concern:

Be it known that I, CHARLES T. E. GOULD, a citizen of the United States, residing at Chicago, in the county of Cook and State of Illinois, have invented certain new and useful Improvements in Sewing-Machines, of which the following, taken in connection with the drawing, is a description.

My invention relates to certain improvements in sewing machines, which may be applied to various makes of machines, and has reference more especially to the bed plate, throat plate and feed mechanism, and which consists of certain novel forms of construction and arrangement hereinafter set forth.

The primary object of the invention is the construction of a bed plate of the class described in my Patent No. 884,482, issued April 14, 1908, which when closed will present the same flat smooth surface of an ordinary machine upon which any kind of sewing may be done, and which can, without removing any fastenings or other parts 25 of the machine be changed into a sectional bed plate, whereby circular garments such as stockings, sleeves, bands, or the like, which it is impossible to sew or mend upon the flat plate, may be slipped over one section of my improved bed plate and be directly beneath the needle and can be as readily sewed as a straight seam.

A further object of my invention is to so construct the bed plate that the sewing 35 mechanism, whether in a lock stitch or a chain stitch machine, will be arranged to extend parallel with the arm of the machine and to be encompassed within a small space and completely incased so that none of the 40 parts are exposed or liable to come into contact with the material being sewed.

A further object of my invention is to provide a throat plate which is very simple in construction, but which is adapted to be 45 used for sewing light or heavy material with fine or coarse thread and may be used on either a lock stitch or chain stitch machine, and after being once adjusted in place it is not necessary to remove the same in order 50 to arrange the machine for different kinds of sewing.

Other objects and advantages of construction will be hereinafter pointed out and claimed in the following description.

In the accompanying drawings I have 55 shown what I now consider to be the preferred form of my construction, although it is obvious that details thereof, and the size and relative proportions of the parts may be changed without departing from the 60 spirit thereof, and in these drawings Figure 1 is a side elevation of the bed plate and the mechanism inclosing casing beneath it; Fig. 2 is a plan view partly in section; Fig. 3 is a sectional view taken on line 3—3 of Fig. 2 65 showing the slide pushed back and the bed plate open; Fig. 4 is a like view taken on the same line, but with the slide closed; Fig. 5 is a sectional view of a removable block in the table of the machine, taken on line 70 11—11 of Fig. 2; Fig. 6 is a section through the throat plate; Fig. 7 is a sectional view of the bed plate taken on line 8—8 of Fig. 2; and Fig. 8 is a sectional view of the end cap 75 of the inclosing casing.

A represents the bed plate of the machine, which is preferably made of metal, although any material suitable for the purpose may be employed.

A' is the head of the machine which is 80 mounted upon the rear portion of the upper face of the bed plate which may be of any well known form of construction to support the necessary operating mechanism, and which alone forms no part of my invention, 85 therefore no detailed description thereof will be given.

Disposed beneath the bed plate is the bobbin or shuttle operating mechanism, which in the form illustrated is the rotary 90 type, and which is inclosed in a close fitting metal casing A² which is secured to the bed plate and completely closes the operative mechanism beneath the bed plate, so that by 95 no possibility can the material being sewed come in contact with said mechanism.

The bed plate A is provided upon each side of the longitudinal center thereof with an elongated opening a, a, extending parallel with each other from the left hand end 100 of the bed plate to the head A' of the machine. From the front edge of the head A' and beneath the same to the rear of the bed plate extending in line with the openings a, a, are recesses b', b', in which the sliding 105 plates a², a², are adapted to be moved when it is desired to use said openings. Each of these recesses is provided with a groove d'

hereinafter explained. The sliding plates a^2, a^2 , when closed, form a smooth bed plate as shown in Fig. 4, the sliding plates in this figure being closed while in Figs. 2 and 3 they are moved to the rearward position and the bed plate is formed as shown in Fig. 2 with the openings upon either side of the center thereof. These sliding plates are provided upon each end thereof with a boss 10 a', a' , to limit the movement thereof in either direction and which slide in the grooves d^2 upon the bed plate.

B is a removable block provided with a lug b upon one end thereof which is adapted to enter a socket in the table B', which block abuts against the bed plate A and closes the ends of the elongated openings a, a , as shown in Fig. 2. This block is readily removed from position by grasping 20 the thumb piece b^2 with the fingers and raising it from the table, when it is desired to open the bed plate for special work upon the machine.

Secured to the top of the bed plate in 25 the usual manner is the throat plate C, which may be square, rectangular, oval, or any shape desired and which is provided with the feed openings c and the needle hole c' . The throat plate C is removably attached in the bed plate, and is adapted to be used with machines having either a lock stitch or chain stitch mechanism.

The inclosing casing A^2 is preferably made of metal and is detachably secured to 35 the braces A^3 formed upon the under side of the bed plate A. The removable end cap D which closes the casing A^2 is held in position by frictional engagement with said casing. As will be observed by reference 40 to Fig. 8 of the drawing, when this cap is secured in place on the outer end of said casing A^2 , the vertical wall of the cap will be spaced from the outer end of said casing, thus forming a groove or space d^2 , to retain 45 any oil that may drop from the mechanism inclosed by said casing and cap.

The operation of the machine is as follows: For plain sewing the slides a^2, a^2 are drawn toward the left and closed and the 50 block B is placed in position so that the machine may be operated in the usual manner. When it is desired to mend or sew a circular garment, the block B is removed and the slides a^2, a^2 moved to the left as shown in 55 Fig. 2, leaving the openings a, a , upon each side of the longitudinal center of the machine, when the garment to be stitched is slipped over the middle section of the bed plate and around the casing A^2 so that it

is free to be moved around said section, or 60 lengthwise thereof, as desired.

I claim:

1. In a sewing machine, a bed plate having longitudinal openings upon each side of the center thereof extending a portion 65 of the length of said bed plate, and recesses in said bed plate in line with the aforesaid openings, and sliding sections in said bed plate movable in said recesses and openings, substantially as described.

2. In a sewing machine, the combination 70 of a bed plate having a longitudinal opening upon each side of the center slideable sections movable in said openings, with a casing inclosing the operative mechanism 75 below said bed plate, an end cap fitting said casing and adapted to be held in position by frictional engagement therewith, substantially as described.

3. In a sewing machine, the combination 80 of a bed plate having longitudinally sliding sections therein, an inclosing casing secured longitudinally to the bottom of said bed plate, an end cap detachably secured around one end of said casing and providing a groove between the closed end of the cap and the adjacent end of the casing, as and for the purpose specified.

4. In a sewing machine, the combination 90 of the table having a bed plate mounted thereon, said bed plate having elongated longitudinally extended openings on each side of the longitudinal center thereof, a removable throat plate secured in said bed plate at the free end of the central section 95 thereof, a casing inclosing the operative mechanism beneath the central section of the bed plate, and a removable block in the table opposite the free end of said central section and outwardly of the throat plate, 100 substantially as described.

5. In a sewing machine, a bed plate having longitudinal openings upon each side of the center thereof, movable slides in said openings, a case secured to the under side of the bed plate between the openings, and a cap detachably secured around one end of 105 said case with its closed end at a distance from the adjacent end of the case, thereby forming a groove for the reception of oil, 110 substantially as described.

In testimony whereof, I have hereunto signed this specification in the presence of two subscribing witnesses.

CHARLES T. E. GOULD.

Witnesses:

JOHN C. BROWN,
CHAS. C. TILLMAN.
